7 Claims. (Cl. 214—82)

1

This invention relates to a loader of the type now commonly used on farms for general loading purposes, and more particularly to a loader that can be readily applied to a farm tractor.

An object of this invention is to provide an improved loader which may be economically manufactured from pipe and may be very easily applied to existing farm tractors without any changes in the tractor proper.

Another object of this invention is to provide a simple and improved mechanism for discharging the contents of the so-called sweep, rake, fork, bucket or the like, of a loader.

Still another object of this invention is to provide a loader wherein a haybuck or fork may be interchangeably used with a sweep or bucket, and wherein, irrespective of the type of sweep used, the same lifting and unloading mechanism can be employed.

Yet another object of the invention is to provide a highly simple and inexpensive loader which may be supplied at very low cost to farmers for general loading purposes such as for use in connection with the crops themselves or the handling of packages or boxes.

In accordance with the general features of this invention there is provided in a loading structure, an upright tubular frame, a boom comprising telescoping tubes pivotally carried by the frame, a sweep on the free end of the boom having a slidable back movable forward to dislodge the contents of the sweep, and a second set of telescoping tubes between the frame and sweep back for moving the back forward.

Another feature of the invention relates to the provision of novelty arranged means for pumping a hydraulic liquid from the frame selectively through the tubes of the loader for swinging the sweep upward and downward and for moving the sweep-back forward when it is desired to unload the sweep.

Still other features of the invention relate to the construction of the frame and the provision thereon of clamping plates for enabling the loader to be clamped to the axle of a tractor, as well as the use of a hydraulic pump so located that it can be driven by the usual power take-off at the rear of the tractor.

Other objects and features of this invention will more fully appear from the following detailed description taken in connection with the accompanying drawings which illustrate several embodiments thereof and in which:

Figure 1 is a side view of a tractor showing our novel loader applied thereto, and illustrating by

2

dotted lines how the booms can be extended to swing the buck or hayfork upwardly;

Figure 2 is a fragmentary plan view, partly in section, of the loader mechanism shown in Figure 1 with the tractor omitted;

Figure 3 is a fragmentary end view of the loader shown in Figure 2;

Figure 4 is an enlarged fragmentary plan view of the bucket or sweep shown in Figure 1;

Figure 5 is a side view, partly in section, of the bucket shown in Figure 4, and illustrated by dotted lines how the back of the bucket or sweep can be propelled forwardly to discharge the contents of the sweep;

Figure 6 is a sectional view taken on the line VI—VI of Figure 4 looking in the direction indicated by the arrows and drawn on a reduced scale;

Figures 7 and 8 are fragmentary views similar to Figures 4 and 5 but showing a modified form of load receiving device which is shown in the form of a hayfork or buck; and

Figure 9 is a fragmentary sectional view through the tubes of one of the main booms illustrating one type of arrangement that may be employed in the extension of the boom in response to hydraulic pressure.

As shown on the drawings:

The reference character 10 designates generally a conventional farm type of tractor which includes a prime mover 11, large motor driven rear wheels 12 and a central front steering wheel 13. The steering wheel 13 may be either a double or single wheel, but, as is well known in the tractor art, it is mounted directly under the prime mover 11. At the rear of the prime mover 11 is located, as is customary, a driver's station, including a seat 14 located above a rear axle 15. It is customary in tractors of this type to have a power take-off directly below the seat 14 and we utilize that take-off in this invention for operating a hydraulic pump designated generally by the reference character 16 in Figure 1.

We also propose to mount our loader on and to support it principally from the axle 15.

The loader includes an upright rectangular frame designated generally by the reference character 20 and which is made of parallel vertical pipes or tubes 21—21 and parallel horizontal connecting pipes or tubes 22—22 (Fig. 2).

The upper tube 22 may be provided with a removable plug 23 which, upon removal, will enable the hydraulic fluid to be introduced into the tubular frame 20. We preferably fill this frame up with hydraulic liquid or oil to a level

slightly below the upper horizontal pipe or tube 22 (Figure 3).

The ends of the horizontal tubes 22 are, of course, closed so that the rectangular frame 20 in reality acts as a reservoir for receiving the fluid to be used in operating the booms and rams employed in connection with the manipulation of the sweep or bucket.

Each of the vertical frame tubes 21 has adjustably secured to it a clamping sleeve 24 which carries a clamping plate 25 adapted to be clamped by means of bolts 26, as shown in Figure 1, to a plate 27 on an opposite side of the axle 15. Thus, the loader of our invention may be very easily and quickly attached to or removed from the tractor axle 15.

The vertical position of the loader relative to the axle may be adjusted by adjusting the position of the two clamping sleeves 24-24 on the two tubes 21-21. It will be noted from Figures 1 and 3 that the sleeve 24 comprises a split tube with flanges adapted to be secured together by bolts 28. This is a conventional type of pipe clamp.

Suitably fastened, as by means of welding or the like, to the lower horizontal tube 22 are a pair of spaced journaled sleeves 29-29 (Figure 2) in which is journaled a pipe 30. The pipe 30 extends parallel to the frame tube 22 and has its ends integrally connected with parallel tube assemblies 31-31, which comprise the inner telescoping tubes 31' of a pair of parallel booms 32. These booms by reason of their being connected by the common tube 30 are adapted to swing about the axis of the two bearing sleeves 29-29.

The booms 32 are disposed on opposite sides of the vehicle between the prime mover 11 and the rear wheels 12. Thus the loader does not increase the overall width of the tractor but is within the normal confines of the tractor area.

Each of the booms 32, in addition to including the inner tube 31, includes an outer tube or pipe 33, which, as best shown in Figure 5, is adapted to telescope a tube 34 comprising part of the bottom of the sweep or bucket 35. (Figures 4 and 5.) The tube 33 may be adjustably locked to tube 34 by any suitable means as by a set screw 34a. This will be described more in detail hereinafter.

The forward ends of the two tubes 33-33 are connected by a transverse tube 36 to the rear of the bucket or sweep 35, and to which are pivotally connected the lower ends of a pair of radius or strut bars 37-37. The upper ends of these rods are pivotally supported (as shown in Figure 3) on the upper horizontal tube of the frame 20. It will be noted that there is one of these tubular rods 37 on each side of the prime mover 11, and it is these radius rods which cause the booms 32 to be extended when the sweep or bucket 35 is swung from the lower position shown in Figure 1 to the dotted line upper position shown in the same figure.

In addition, the horizontal frame tube 22 has secured to it the upper ends of a pair of reinforcing tubes 38-38 (Fig. 1). The lower ends of these reinforcing rods or tubes 38 are attached at 39 to the sides of the prime mover 11. This provides a very rigid and firm way of holding the frame 20 in a vertical position. In other words, while the weight of the frame 20 is carried directly on the axle 15 the rods 38 serve to prevent swinging of the frame relative to the axle 15.

Positioned on opposite sides of the tractor and parallel to the booms 32 but above them are a

pair of parallel rams 40 for actuating the back 41 of the sweep or scoop 35.

Each of these rams 40 includes an outer pipe or tube 42 and an inner or telescoping tube 43 for delivering hydraulic fluid into the pipe 42 and against its outermost end at 45 (Figure 5) to move the back 41 of the sweep or scoop forwardly.

Each outer tube 42 has suitably secured to it a sleeve or guide 46 (Figure 1) through which the corresponding boom 32 extends so that the ram is supported by the associated boom. Similarly an end of the boom 32 carries an integral tubular guide 47 through which an end of the outer ram tube 42 extends. Thus on each side of the tractor the ram and boom tubes are so interrelated that they cooperate to assist in supporting each other.

Each of the inner ram tubes 43 is connected by a pipe line including a flexible hose 50 (Figures 1 and 2) to a common pipe 51 disposed parallel to and to the rear of the tubular frame 20. This pipe 51, as best shown in Figure 2, is connected at an intermediate point by a pipe connection 52 to a parallel pipe 53, one end of which is connected by a flexible pipe line 54 to the inlet side of the pump 16, and the other end of which is connected by a flexible pipe line 55 to the discharge side of the pump 16.

It will be noted that one end of the pipe 53 is connected by a pipe connection 56 to the bottom tube 22 of the frame 20 so that hydraulic liquid or oil may be delivered from the reservoir comprising the frame 20 to the pump 16 through the flexible pipe line 54 when a valve 57 in the pipe line 53 is closed.

It should also be noted that an end of the pipe 53 connected to the discharge flexible pipe line 55 by a T-shaped three-way valve connection 58 through which oil can be pumped to operate the booms. The valve 58, which may be a three-way valve, has one of its outlets connected by a pipe line 59, including a flexible hose 60, to the tube 30 which is common to both the booms so that oil can be delivered into both booms from the tube 30. Each of the valves 57 and 58 may be provided with elongated handles 61 and 62 for operating the same, as shown in Figures 1 and 3, and which are accessible to the driver when he is sitting on the seat 14.

Before proceeding with the description of the operation of the machine, we will conclude the description of the sweep or scoop. (Figs. 4 and 5.) It should be noted that the guide tubes 34 comprise integral extremities of a common plate 65. These tubes may be welded to the ends of the plate. The plate may have in turn secured to it on its underside a plurality of spaced forks 66. The end forks may have secured to them, as by welding, side plates 67-67. Also, if it is so desired, a plate 68 may be welded to the forward ends of the forks in advance of the plate 65 as shown in Figure 4.

Thus all the parts of the sweep or scoop 35, with the exception of the back plate 41, are integrally joined or welded together. As shown in Figure 6 the back plate 41 may have its corners notched out at 69 so as to slide the over curved surfaces of the two end tubes 34-34.

The back plate 41 also has secured to it a pair of spaced cups 70 in each of which an end of a ram tube 42 is tightly secured at 45. The ends of the ram tubes at 45 may be suitably closed or capped so that the fluid forced therein

by the pump 16 will not leak out of the connection between the ram and back plate 41.

When the valves 57 and 58 are properly manipulated so that hydraulic fluid is pumped from the pump 16 into the two rams 40-40, the outer tubes 42 of the rams are moved forward thus pushing the back plate 41 from the full line position shown in Figure 5 to the dotted line position.

We find it desirable to provide mechanical means for returning the back plate 41 after each unloading operation. This mechanism comprises an arm 72 pivotally mounted on the pipe 36 and having its free end connected by a wire or chain 73 to the back plate assembly 41. A coil spring 74 is disposed around the tube 36 and has one end anchored at 75 to the tube 36; the other end is anchored at 76 to the pivotal arm 72 (Figures 4 and 5).

This arrangement is such that upon forward movement of the sweep-back 41 to discharge the contents of the sweep or scoop, the arm 72 is pulled to the dotted line position shown in Figure 5 thus tightening the coil spring 74 whereby upon release of the hydraulic pressure, the spring becomes effective through the arm 72 to return the sweep-back 41 from the dotted line position shown in Figure 5 to the full line position.

It will be appreciated that there are many other mechanical devices that could be used for this purpose although the one we have disclosed herein is a relatively cheap one to manufacture.

Each of the pair of tubes 33 is provided with a stop or abutment 78 for limiting the movement of the back 41 to its normal position, which is shown in Figure 5 in full lines. Each of the pair of tubes 33 is also provided with a stop or abutment 79 extending into the interior of the tube, the purpose of which will now be described in connection with Figure 9.

Each of the boom assemblies 32 includes, as we have noted before, an inner tube assembly 31 and an outer tube 33 (Figure 9). When the telescoping tubes of the boom are not relatively extended the outer tube 33 has a gland 80 abutting an end or shoulder 81 of the inner tube assembly 31. It should be noted that the inner tube 31 of each boom has integral with it an inner tube 31' which extends in outer boom tube 33.

When fluid, however, is delivered through the tube 30 into the interior of the booms that fluid is caused to act upon a floating piston assembly 82 inside of the inner tube 31. This assembly 82 includes the usual bicycle pump type of cup leathers 83 mounted on one end of a rod 84, the other end, which is provided with a head 85 for striking the abutment 79, extending into the interior of the tube 33. Thus when pressure is applied to the piston 83 the head 85 presses against the abutment 79 thereby forcing the outer tube 33 along the inner tube 31' in a direction away from the main frame 20. This results in the pushing force being applied to the scoop or sweep 35.

Obviously since the forward movement of the sweep is restrained by the radius rods 37, the scoop, of necessity, is forced to swing upwardly with its load to the dotted line position as shown in Figure 1.

Any suitable piston mechanism can be employed for operating the booms and arms, although we have found the structure we have disclosed to be a simple and cheap one to manufacture.

In Figures 7 and 8 we have illustrated a modified form of sweep which, instead of being of the scoop type as shown in Figures 4 and 5, is of the fork or buck type. In this form of the invention, the bottom of the scoop comprises a plurality of forks or prongs 100 joined together by a common rod 101. This rod 101, as well as a parallel rod 102, may be suitably welded to the prongs. Suitably secured to rod 102 are the sockets or tubes 34', in which the ends of the outer tubes 33 of the booms are socketed. Any suitable means may be provided for locking the end of the boom tube to the socket 34', such as a set screw 90.

The haybuck 100 also has a slidable back 105 which is mounted on ram rod tubes 42 to be reciprocable therewith in the same manner as is true in the case of the back 41 of the previously described sweep 35.

As in the first form of the invention, a spring urged arm 72 is connected to the back by means of a cable 73 (Figure 8) for retracting the back and ram tubes 42 after each sliding operation of the back along the forks 100. In addition, the back may, if it is so desired, be provided with spaced wire stays 110 connected to sleeves 111 (Figure 8) adapted to slide along the boom tubes 33 when the back is moved forward over the forks 100.

In the use of our device the tractor is moved forward so that the sweep, scoop or buck is dug into the material to be lifted and is in that manner filled. During this filling operation the buck or sweep, as the case may be, is in the position shown in Figure 1. The operator then turns on the pump 16 through any suitable driving connection, closes the valve 57 and opens the valve 58 (Figure 2) so as to connect the pump discharge pipe line 55 with the pipe line 59.

This results in the pump directly forcing fluid or liquid into the interior of tube 30 and into the tube booms 32. The hydraulic liquid under pressure acts upon the piston assemblies 82 in each of the booms and causes the outer boom tubes 33 to exert a pressure against the sweep or buck for thus swinging it up to the dotted line position shown in Figure 1.

It will, of course, be appreciated that the arc of movement of the sweep or buck is determined by the radius rods 37 which causes the buck or sweep to move upwardly. During this upward movement the outer boom tubes 33 are extended outwardly over the inner tubes 31', as shown by the dotted lines in Figure 1. Similarly in the case of the rams 40 the outer tubes 42 are extended outwardly over the inner tubes 43 as shown by the dotted lines.

Now, when it is desired to eject the contents of the sweep or buck, the operator manipulates the valve 58 to place the discharge pipe line 55 in communication with the pipe 53 which delivers fluid to the pipe 51 in communication with the two sets of ram tubes 40-40. In this condition the valve 57 must be closed so that the fluid will not be pumped back into the reservoir frame 20.

After the back of the sweep has been moved forward to eject the contents of the sweep or buck, the operator manipulates the valve 57 so that the pressure is relieved and the fluid that is being pumped is then pumped back into the reservoir rather than into the booms or rams. Thereafter, the energy stored up behind the spring arm 72 of the sweep or horn functions to return the back of the sweep to its original position.

tion pushing the liquid back into the reservoir.

Similarly, the weight of the booms and the sweep causes the sweep to be moved downwardly; this weight also acting to push the liquid in the extended boom back into the reservoir frame 20 and thus restoring the booms to their original telescoping relationship.

As noted before, the sweep may be in the form of a scoop 35 or in the form of a haybuck 199. These two devices are interchangeable in our loader assembly.

The principal parts of our loader may be made from conventional pipe to which other parts that are to make up the assembly may be easily welded and interfitting therewith. Ends of the pipe may be suitably closed or plugged where same is necessary.

Another feature of our invention, as will be noted from Figure 1, relates to the fact that the device, when the sweep is in its lowermost position, can be easily moved with the tractor into the barn since it does not project very high above the tractor, as is the case with many existing loading devices. In fact, the arrangement of the loader with respect to the tractor is such that it occupies very little space over and above that normally occupied by the tractor.

The compactness of the loader together with the ram action makes it possible for a farmer to load manure directly into the spreader and right in the cattle shed.

When used in the field, the loader lifts shocks of grain smoothly and takes them to the thresher with no damage to the heads.

The frame and the relation of the booms and rams with respect thereto enables a correctly balanced loader with a proper distribution of weight. This arrangement is such that it does away with the possibility of the tractor tipping under heavy loads.

Moreover, by using an electrically welded steel tube frame in the loader we eliminate the hazards of the parts and bolts working loose. This is important in the rough use to which devices of this character are put on farms and the like.

In the accompanying claims we have used the term "sweep" in a generic sense to refer to either a bucket, a scoop, a horn, a hay fork, rake or other similar loading device.

We claim as our invention:

1. In a loading and stacking structure an upright frame, a boom comprising telescoping tubes pivotally carried by said frame, a strut pivotally connected to an upper portion of said frame and to the forward portion of said boom, a sweep on the free end of the boom having a slidable back movable forward to dislodge the contents of the same, a ram comprising a second set of telescoping tubes between said frame and said back for moving the back forward to discharge the contents of the sweep, said frame comprising interconnected tubes formed to define a reservoir for a hydraulic medium, and means for pumping the hydraulic medium selectively through said tubes for swinging the sweep upwardly and moving the sweep-back forward when it is desired to unload the same, said means including a floating piston in the tubes of the boom engageable upon being impelled by the pumped liquid with an abutment on one of the tubes of the boom for carrying that tube forward to elevate the sweep.

2. In a loading and stacking structure an upright frame, a boom comprising telescoping tubes pivotally carried by said frame, a strut pivotally

connected to an upper portion of said frame and to the forward portion of said boom, a sweep on the free end of the boom having a slidable back movable forward to dislodge the contents of the same, a ram comprising a second set of telescoping tubes between said frame and said back relatively extendable by hydraulic pressure for moving the back forward to discharge the contents of the sweep, said sweep-back having connected to it a spring in which energy is stored up when the back is moved forward whereby upon release of hydraulic pressure on said back said spring will return said back to its initial position and at the same time restore the telescoping ram tubes to their original relative positions.

3. In a loading and stacking structure, an upright frame, a boom comprising telescoping tubes pivotally carried by said frame, a sweep on the free end of the boom having a slidable back movable forward to dislodge the contents of the sweep, a strut pivotally connected to said frame and secured to said sweep, a ram comprising a second set of telescoping tubes between said frame and said back relatively extendable by hydraulic pressure for moving the back forward to discharge the contents of the sweep, said sweep-back having connected to it means in which energy is stored up when the back moves forward whereby by release of hydraulic pressure on said back said means will return said back to initial position and at the same time restore the telescoping ram to its original relative position.

4. In a loading and stacking structure an upright frame, a boom comprising telescoping tubes pivotally carried by said frame, a sweep on the free end of the boom having a slidable back movable forward to dislodge the contents of the sweep, a strut pivotally connected to said frame and secured to said sweep, a ram comprising a second set of telescoping tubes between said frame and said back relatively extendable by hydraulic pressure for moving the back forward to discharge the contents of the sweep, said sweep-back having connected to it a resilient means in which energy is stored up when the back is moved forward whereby by release of hydraulic pressure on said back said resilient means will restore said back to its initial position and at the same time restore the telescoping ram to its original relative position.

5. In a loading and stacking structure, an upright frame, a boom comprising telescoping tubes pivotally carried by said frame, a sweep on the free end of said boom having a slidable back movable forward to dislodge the contents of the same, a strut pivotally connected to said frame and secured to said sweep, a ram including tubular means actuated by hydraulic pressure for moving the back forwardly to discharge the contents of the sweep, said frame having a reservoir for hydraulic medium, means for pumping the hydraulic medium selectively through said tubes and said tubular means for swinging the sweep upwardly and moving the sweep-back forward when it is desired to unload the same, and means including a floating piston in the tubes of the boom engageable upon being impelled by the pumped liquid with an abutment on one of the tubes of the boom for carrying that tube forward to elevate the sweep.

6. In a loading and stacking structure an upright frame, a boom comprising telescoping tubes pivotally carried by said frame, a sweep on the free end of the boom having a back member mov-

able relative to the bottom plate of said sweep to dislodge the contents of the same, a strut pivotally connected to said frame and secured to said sweep, a ram comprising a second set of telescoping tubes between said frame and said back for causing relative movement of the back and the bottom plate to discharge the contents of the sweep, said frame comprising interconnected tubes formed to define a reservoir for hydraulic medium, means for pumping the hydraulic medium selectively through said tubes for swinging the sweep upwardly and causing relative movement of the back and bottom plate of the sweep when it is desired to unload same, and means including a floating piston in the tubes of the booms engageable upon being impelled by the pumped liquid with an abutment on one of the tubes of the boom for carrying that tube forward to elevate the sweep.

7. In a loading and stacking structure, a frame, a sweep, a strut pivotally secured to said frame and secured to said sweep, a first pair of tubes, a tube connecting the ends of said pair of tubes, means securing said connecting tube to said frame for rotation about its axis, a second pair of tubes telescoping with said first pair of tubes and connected to said sweep, a reservoir for a hydraulic medium, means for pumping the hydraulic medium into said connecting tube, and piston means in each of said first pair of tubes actuatable by the hydraulic medium and connected with the corresponding one of said second

5

pair of tubes for extending said second pair of tubes to raise said sweep upon pumping of the hydraulic medium into said connecting tube.
